(57) **CLAIM**

The ornamental design for a smoke alarm as shown and described.

DESCRIPTION

FIG. 1 is a left, front perspective view of a smoke alarm showing my new design;

FIG. 2 is a front elevational view of the smoke alarm of FIG. 1;

FIG. 3 is a rear elevational view of the smoke alarm of FIGS. 1 and 2;

FIG. 4 is a left side elevational view of the smoke alarm of FIGS. 1-3;

FIG. 5 is a right side elevational view of the smoke alarm of FIGS. 1-4;

FIG. 6 is a top plan view of the smoke alarm of FIGS. 1-5; and,

FIG. 7 is a bottom plan view of the smoke alarm of FIGS. 1-6.

The portions of the article shown in broken lines form no part of the claimed design.

1 Claim, 7 Drawing Sheets
